EDWARD E. HILER, OF BLOOMFIELD, NEW JERSEY

AUDIO AMPLIFICATION SYSTEM

Application filed July 13, 1929. Serial No. 378,058.

This invention relates, generally, to electron tube amplification systems; and the invention has reference, more particularly, to push-pull audio frequency amplifier circuits. Heretofore common use has been made of transformer coupled push-pull audio amplification wherein in the input circuit the secondary winding of an audio transformer is center tapped to the filament or ground portion of the circuit and the outer terminals of this secondary winding are connected to the grids of the thermionic tubes. This arrangement eliminates the effect of the generation of second harmonics in the electron or thermionic tubes, for by thus arranging the tubes in the circuit, the operation is such that during any one cycle the voltage impressed on the grid of one tube is increasing while that impressed on the grid of the other tube is decreasing. The grid or input circuits of the tubes are therefore, 180 degrees out of phase causing the fundamental currents in the two plate circuits to differ in phase by 180 degrees. A center tapped coil may be used in the output circuit of the tubes in lieu of a transformer in which case the center tap of the coil is connected to the positive terminal of a "B" battery, and the end terminals of this coil are connected to the plates of the two tubes. With this arrangement, the fundamental signal in passing from the plate of one tube through the output coil to the center tap is 180 degrees out of phase with the fundamental signal passing from the plate of the other tube to the center tap. Thus, owing to the push pull arrangement, the currents passing from the plates of the tubes through the sections of the coil are in phase, causing their magnetic fields to be additive as desired. However, the distortion produced in each of the tubes due to the curvature of the tube characteristic occurs at the same time and in the same direction in each of the tubes with the result that second harmonics generated in the tubes are in phase and are balanced out in the output circuit as desired.

The use of audio transformers in the input circuits of such amplification systems, however, results in more or less distortion due to the impossibility of obtaining one hundred

percent coupling between the primary winding and the tapped secondary winding of the transformer. Furthermore, in using input transformers in such circuits it is generally necessary to employ resistances in shunt with the secondaries of the transformers in order to reduce the undesirable effects of resonance peaks, the use of which resistances not only complicates the circuit but adds to the cost thereof.

The principal object of this invention is to provide a novel push-pull audio frequency amplifier circuit employing double impedance coupling in lieu of transformer coupling.

The use of double impedance coupling has decided advantages over transformer coupling one of which advantages lies in the elimination of shunt resistances, since capacity coupling is employed instead of magnetic coupling, which design eliminates the resonant peaks at the high frequencies. On account of not having a cut off at the high frequencies, the range of frequencies made possible by using double impedance coupling can be extended to cover the wide band of frequencies necessary for reproduction in high quality music and television applications.

By utilizing the method outlined in my prior Patent No. 1,715,501 the low audio frequencies below 150 cycles can be exaggerated, if desired, to compensate for the normally poor reproduction of low frequencies in loud speaker operation.

Other objects of this invention not at this time more particularly enumerated will be clearly understood from the following detailed description of the same.

The invention is clearly illustrated in the accompanying drawing, in which:

Fig. 1 is a wiring diagram of the preferred form of the invention, and

Fig. 2 illustrates an alternative manner of connecting a speaker or telephone receiver in the output circuit.

Referring now to Fig. 1 of the said drawing, the reference character 1 designates a three-electrode thermionic electron tube or device which may be employed as a detector or as an audio amplification tube represent-

- ing a stage of audio amplification. The grid 2 and filament or cathode 3 of tube 1 may be connected to any suitable input circuit, the output of which it is desired to amplify.
- 15 The filament 3 of tube 1 may be heated by current supplied by a battery 14 while the plate or anode 4 of this tube is illustrated as supplied through a choke coil 15 with voltage from a "B" battery 16.
- 10 The plate 4 of tube 1 is connected through a coupling condenser 5 to the grid of a three-electrode tube 6 arranged in opposition or push-pull relation with a similar tube 7. Battery 14 is illustrated as supplying heating current to the filaments of tubes 6 and 7.
- 15 The grid of tube 7 is connected through a grid choke coil 8 and condenser 5 to the plate of tube 1. The center of the grid choke coil 8 is tapped and is connected from this midpoint through a "C" battery 9 to the filaments of tubes 6 and 7 and therefore the potentials impressed on the grids of tubes 6 and 7 are 180 degrees out of phase, causing the fundamental currents in the plate circuits of these tubes to differ by 180 degrees while the harmonics will be in phase. Looked at in another way, the lower half of the grid choke coil 8 is in effect the secondary of a one to one transformer, the primary of which is 20 the upper half of the coil. The upper half of this coil serves as a grid choke for tube 6 while at the same time it is acting as a primary for the lower half of the coil.
- 25 The plates of tubes 6 and 7 are connected to the terminals of an output choke coil 11. The center of choke coil 11 is tapped and is connected through "B" batteries 12 and 16 to the filaments of tubes 6 and 7. Owing to the push-pull arrangement of tubes 6 and 7, though the fundamental currents in the plate circuits of these tubes differ by 180 degrees, yet the magnetic fields set up by these currents in the output choke coil 11 are additive while those set up by the harmonics 30 are opposed and offset each other.
- 35 A loud speaker or telephone 13 is illustrated as connected in shunt across the terminals of output choke coil 11 for reception purposes.
- 40 In operation, the output of tube 1 impresses an alternating current potential across choke coil 15. Since condenser 5 and choke coil 8 are connected through common batteries, these members are arranged in 45 shunt with choke coil 15 and therefore an alternating current potential of substantially the same value as impressed across coil 15 is impressed upon choke coil 8 since there is but little drop in potential across condenser 5.
- 50 An alternating current potential is therefore applied to the grid of thermionic device 6. Since the lower half of coil 8 is magnetically coupled to the upper half thereof, an alternating current potential is impressed 55 on the grid of tube 7 which potential how-

ever, increases simultaneously with a decrease in potential impressed on the grid of tube 6.

Assuming at any instant that the grid potential of tube 6 causes the fundamental output A. C. current of this tube to flow from the center tap of coil 11 in a direction toward the plate of tube 6, then there will be caused by the grid potential of tube 7 an output current flowing in a direction from the plate of tube 7 toward the center tap of coil 11, so that these currents are additive in this coil. As is well known to those skilled in the art the voltages impressed on the grids of these tubes generate harmonics which are in phase 80 and which therefore balance out in the output circuit.

It will be apparent that the loud speaker or telephone 13 may be connected in the output circuit in various other ways other than that shown in Fig. 1. That is, there are various ways of completing the output circuit from the points A—A' of Fig. 1. For example, as shown in Fig. 2 of the drawing a different type of circuit arrangement is 90 employed from the points A—A'. In this arrangement the center tapped output choke coil is eliminated and in lieu thereof impedances 16' and 17, illustrated as choke coils, 95 may be employed. Choke coils 16' is connected to the plate speaker circuit of tube 6 whereas choke coil 17 is connected to the plate speaker circuit of tube 7. In operation, the fundamental currents in these plate speaker circuits are additive in the 100 speaker 13, whereas the harmonics are opposed and hence cancel one another.

It is obvious that non-inductive resistances may be used in lieu of choke coils 16 and 17 if desired. Also many other ways may be employed for completing the circuit from the points A—A', as for instance by using an output transformer with the primary winding center tapped to the output of the tubes. Although the electrodes of the thermionic 110 devices are illustrated for the sake of simplicity, as supplied with electric energy from battery sources, it is to be understood that normally an a. c. supply would be employed.

As many changes could be made in the 115 above construction and many apparently widely different embodiments of this invention could be made without departing from the scope thereof, it is intended that all matter contained in the above description or shown in the accompanying drawing shall be interpreted as illustrative and not in a limiting sense.

What is claimed is:—

1. An electrical amplification system comprising in combination, an electron discharge device adapted to have its grid and cathode elements connected to an input circuit, an anode choke coil, said discharge device having its anode supplied with positive poten- 125

5 tial through said anode choke coil, a condenser, and transformer means, said transformer means having a primary winding and a secondary winding, said condenser and said primary winding being arranged in parallel with said anode choke coil, a pair of oppositely arranged electron discharge devices having cathode-grid circuits, one of said discharge devices having its cathode-
10 grid circuit connected across the primary winding of said transformer means and the other of said discharge devices having its cathode-grid circuit connected across the secondary winding of said transformer means.
15 2. In a push-pull double impedance circuit for audio amplification, in combination, a pair of thermionic tubes having cathode-grid circuits, transformer means having primary and secondary windings, said transformer means having its primary winding included in one of said circuits, and its secondary winding included in the other of said circuits, a coupling condenser for coupling said thermionic tubes to a signal circuit, a
20 25 plate choke coil, said plate choke coil being connected to said coupling condenser, and said transformer means primary winding serving as a choke coil for one of said cathode-grid circuits.
30 3. In an audio amplifier circuit, in combination, a pair of electron discharge devices, each of said devices having a grid element together with a cathode and anode, external circuits extending between the cathode and grid elements of each of said devices, and transformer means having a primary winding and a secondary winding solidly connected in series, said transformer means having its primary winding connected in the
35 40 45 external circuit of one of said devices and its secondary winding connected in the external circuit of the other of said devices, and a coupling circuit connected at one side to the primary winding of said transformer means and at the other side to the cathode elements of said devices, whereby the primary winding of said transformer means is arranged in series with said coupling circuit.
50 4. In an audio amplifier circuit, in combination, a pair of electron discharge devices connected in opposition, each of said devices having a grid element together with a cathode and anode, external circuits extending between the cathode and grid elements of each of said devices, and transformer means having a primary winding and a secondary winding solidly connected in series, said transformer means having its
55 60 65 primary winding connected in the external circuit of one of said devices and its secondary winding connected in the external circuit of the other of said devices, and a coupling circuit having a condenser therein, said coupling circuit being connected at one side to

the primary winding of said transformer means and at the other side to the cathode elements of said devices, whereby said condenser and the primary winding of said transformer means are arranged in series in said coupling circuit.

In testimony, that I claim the invention set forth above I have hereunto set my hand this 12th day of July, 1929.

EDWARD E. HILER.
